(57) **CLAIM**

The ornamental design for a fishing rod reel seat as shown and described herein.

DESCRIPTION

FIG. 1 is an upper perspective view of the fishing rod reel seat showing the new design;

FIG. 2 is a lower perspective view of the fishing rod reel seat of FIG. 1 showing the new design;

FIG. 3 is a front view of the fishing rod reel seat of FIG. 1 showing the new design;

FIG. 4 is a rear view of the fishing rod reel seat of FIG. 1 showing the new design;

FIG. 5 is a top plan view of the fishing rod reel seat of FIG. 1 showing the new design;

FIG. 6 is a bottom plan view of the fishing rod reel seat of FIG. 1 showing the new design;

FIG. 7 is a right side view of the fishing rod reel seat of FIG. 1 showing the new design;

FIG. 8 is a left side view of the fishing rod reel seat of FIG. 1 showing the new design; and,

FIG. 9 is a cross-sectional view of the fishing rod reel seat of FIG. 8 showing the new design.

The broken lines depict portions of the finishing rod reel seat that form no part of the claimed design.

1 Claim, 8 Drawing Sheets
